UNITED STATES PATENT OFFICE

LEAH G. MILKES, OF CHICAGO, ILLINOIS.

DESIGN FOR AN OVERSHOE OR SIMILAR ARTICLE.

Application filed February 3, 1928. Serial No. 25,155. Term of patent 14 years.

To all whom it may concern:

Be it known that I, LEAH G. MILKES, a citizen of the United States, residing at Chicago, in the county of Cook and State of Illinois, have invented a new, original, and ornamental Design for an Overshoe or Similar Article, of which the following is a specification, reference being had to the accompanying drawing, forming part thereof.

In the drawing,—

Fig. 1 is a perspective view of the right side of an overshoe showing my new design; and

Fig. 2 is a perspective view of the left side of the same.

I claim:—

The ornamental design for an overshoe or similar article, substantially as shown.

LEAH G. MILKES.
